INTERVAL CONTROL MECHANISM

Earle L. Kent, Elkhart, Ind., assignor to C. G. Conn, Ltd., Elkhart, Ind., a corporation of Indiana

Application January 5, 1944, Serial No. 517,025

7 Claims. (Cl. 200—33)

1

This invention relates to interval control mechanism and more particularly to switching mechanism for supplying an electrical impulse of predetermined duration.

One of the objects of the invention is to provide interval control mechanism in which the duration of an electrical impulse can be accurately adjusted. In the construction shown the duration of an impulse can be adjusted in fractions of a micro second.

Another object is to provide interval control mechanism in which duration of an impulse is determined by a pair of spaced brushes moving over a contact drum. Adjustment of the interval is accomplished in this construction by adjusting the relative positions of the brushes to vary the time both brushes engage a conducting portion of the drum.

Still another object of the invention is to provide interval control mechanism in which safety means are provided to prevent closing a circuit between the brushes during resetting of the mechanism.

The above and other objects and advantages will be more readily apparent from the following description when read in connection with the accompanying drawing, in which—

Figure 1 is a plan view of an interval control mechanism embodying the invention; and

Figures 2 and 3 are partial diagrammatic views showing the mechanism in different positions.

The apparatus shown in Figure 1 comprises a base 10 on which is mounted an electric motor 11. The motor is preferably a synchronous or constant speed motor of sufficient power to drive the apparatus without any substantial variation in speed during the cycle of operations. As shown, the motor may be controlled by a switch 12.

The motor shaft carries at its outer end a drum 13 as shown in Figures 2 and 3 formed with insulated end portions 14 and a conducting central portion 15. The several portions of the drum are connected along helical lines 16 terminating in abrupt shoulders 17. While the drum has been shown with the ends of insulating material and the center portion of conducting material, it will be understood that this arrangement could be reversed.

A carriage is provided movable axially of the drum and as shown in Figure 1 is formed by a sleeve 18 fitting over the drum. The sleeve carries a pair of spaced brushes one indicated at 19 being fixed in the sleeve and the other shown at 20 being carried by a collar 21 which is threaded on the sleeve. The threads connecting the collar 21 to the sleeve are preferably of the same axial pitch as the helical lines 16.

The carriage is held against rotation while being permitted to move axially of the drum by a pair of arms 22 pivoted to the carriage at one end

2

and at their opposite ends pivoted to a block 23 on the base. These arms being parallel serve to guide the carriage and hold it against rotation while permitting it to move along the drum.

In operation the drum is rotated and the carriage is moved along it from initial position shown in Figure 2 to a final position shown in Figure 3. In the initial position the brush 19 engages the conducting portion 15 of the drum, while the brush 20 engages the insulating portion 14 at one end of the drum. As the carriage is moved axially of the drum, the brush 20 will pass across the shoulder 17 on to the conducting portion 15 to establish a circuit between the brushes. This circuit will be maintained until the leading brush 19 moves across the shoulder 17 at the right end of the drum to interrupt the circuit. Thus the interval during which the circuit is maintained will depend upon the relative positions of the brushes.

In order to adjust the brush 20 to provide the desired interval, the collar 21 is formed at one end with scale markings having calibrations 24 thereon for one scale indication and calibrations 25 for a second scale indication. Preferably the two scale indications are in different colors so that they may be readily distinguished. One of the scale indications cooperates with a reference mark 26 on the sleeve 18 and the second scale indications cooperate with a similar axially spaced mark 27. The marks 26 and 27 may be colored to correspond to the scales for easy reading. As the collar is turned indications are first obtained on the scale 24 opposite the reference mark 26, the reference mark 27 at this time being spaced axially from the collar. As the collar is turned further it moves up on the reference mark 27 and the interval may then be read opposite this mark on the scale 25. The scales are preferably calibrated in micro seconds so that the interval can be adjusted accurately in fractions of a second.

The carriage is moved along the drum by a feeding mechanism including a cylindrical feed member 28 on the motor shaft having plain cylindrical end portions 28 with a helical thread 29 therebetween. The pitch of the thread 29 is the same as that of the helical lines 16 so that as the carriage is advanced the brushes will move parallel to the lines 16.

The carriage has pivoted thereon a lever 31 which carries at one end a follower pin 32 adapted to engage the threads 29 to advance the carriage. The lever 31 may be normally urged in a position to engage the feed member by a spring or the like not shown and may be moved out of engagement with the feed member by a handle 33 on the end of the lever.

The carriage is shown in Figure 1 in its initial position in which the follower pin 32 engages the

cylindrical portion 28 to the left of the threads 29. The carriage is urged toward the threads by a spring 34 and is held in its initial position against a spring tension by a latch 35. Preferably, adjustable stops 36 and 37 are provided to limit the initial and final positions of the carriage.

To operate the mechanism with its carriage in initial position as shown in Figure 1 and with the motor 11 running, the latch 35 is released. The spring 34 then moves the carriage to the right until the follower pin 32 engages the threads 29. The carriage will continue to move at a rate determined by the threads to close a circuit between the brushes 19 and 20 for a predetermined interval as explained above. When the carriage has moved over against the stop member 37 the follower pin 32 will ride on the cylindrical portion 28 at the right of the feed member.

To reset the mechanism the lever 31 is swung clockwise to raise the follower pin 32 above the point where it will engage the threads 29. The carriage will then be moved to the left until the latch 35 is engaged at which time it is set for another operation.

In order to prevent accidental completion of a circuit between the brushes during resetting, a switch 38 is provided on the carriage in circuit with the brushes. The switch 38 is normally closed but is engaged by the lever 31 when it is operated to move the follower finger away from the feed member to be opened. Thus, during resetting it is impossible to establish a circuit through the brushes.

While one embodiment of the invention has been shown and described in detail herein, it is understood that this is for the purpose of illustration only and is not to be taken as definition of the scope of the invention, reference being had to the appended claims for this purpose.

What is claimed is:

1. Interval control mechanism comprising a rotatable contact drum having adjacent conducting and insulating portions joined along helical lines, a carriage movable axially of the drum, means to move the carriage at a substantially constant rate, a pair of spaced brushes on the carriage engageable with the drum, and means mounting one of the brushes on the carriage for adjustment about the drum axis along helical lines having the same axial pitch as the first named helical lines to vary the helical distance around the drum surface between the brushes.

2. Interval control mechanism comprising a rotatable contact drum having adjacent conducting and insulating portions joined along helical lines, a carriage movable axially of the drum, a feed screw rotatable with the drum having the same axial pitch as said helical lines, means on the carriage engageable with the feed screw to move the carriage axially of the drum, a pair of brushes on the carriage engageable with the drum, and means mounting one of the brushes on the carriage for adjustment around the drum in a helical path having the same axial pitch as the feed screw and said helical lines.

3. Interval control mechanism comprising a rotatable contact drum having adjacent conducting and insulating portions joined along helical lines, a carriage movable axially of the drum, a feed screw rotatable with the drum having the same axial pitch as said helical lines, means on

the carriage engageable with the feed screw to move the carriage axially of the drum, a pair of brushes on the carriage engageable with the drum, a collar threaded on the carriage coaxial with the drum carrying one of the brushes, the threaded connection between the collar and carriage having the same axial pitch as the feed screw and said helical lines.

4. Interval control mechanism comprising a rotatable contact drum having adjacent conducting and insulating portions joined along helical lines, a carriage movable axially of the drum, a feed screw rotatable with the drum having the same axial pitch as said helical lines, means of the carriage engageable with the feed screw to move the carriage axially of the drum, a pair of brushes on the carriage engageable with the drum, a collar threaded on the carriage coaxial with the drum carrying one of the brushes, the threaded connection between the collar and carriage having the same axial pitch as the feed screw and said helical lines, the collar having a pair of graduated scales at one end, and a pair of axially spaced index marks on the carriage cooperating with said scales respectively to indicate the interval during which the brushes are electrically connected through the drum.

5. Interval control mechanism comprising a contact drum having conducting and insulating portions, a carriage movable axially of the drum, a pair of spaced contacts carried by the carriage engageable with the drum, a feed screw aligned with the drum, a follower movably mounted on the carriage engageable with the feed screw to move the carriage along the drum, and a switch in circuit with the contacts engaged and opened by the follower when it is moved out of engagement with the feed screw.

6. Interval control mechanism comprising a contact drum having conducting and insulating portions, a carriage movable axially of the drum, a pair of spaced contacts carried by the carriage engageable with the drum, a feed screw aligned with the drum, a lever pivoted on the carriage and carrying at one end a follower engageable with the feed screw to move the carriage along the drum, and a switch on the carriage in circuit with the contacts engaged and opened by the lever when it is swung to a position to disengage the follower from the feed screw.

7. Interval control mechanism comprising a shaft rotatable at a substantially constant speed, a contact drum on the shaft having conducting and insulating portions joined by helical lines, a carriage movable longitudinally of the drum, contacts on the carriage engaging the drum, a collar threaded on the carriage coaxial with the drum on threads having the same axial pitch as said helical lines and carrying one of the contacts, a feed member on the shaft having cylindrical ends and a helical thread between them of the same axial pitch as said helical lines, a follower pivotally mounted on the carriage movable into engagement with the feed member, a switch in circuit with the contacts opened by the follower when it is moved out of engagement with the feed member, a latch for holding the carriage in one end position, and resilient means urging the carriage toward its other end position.

EARLE L. KENT.
